UNITED STATES PATENT OFFICE.

JAMES O'CONNOR, OF NEW YORK, N. Y.

EXPRESSION DEVICE FOR MECHANICAL MUSICAL INSTRUMENTS.

No. 927,587.

Specification of Letters Patent.

Patented July 13, 1909.

Application filed August 8, 1904, Serial No. 219,841. Renewed December 9, 1908. Serial No. 466,637.

To all whom it may concern:

Be it known that I, JAMES O'CONNOR, a citizen of the United States, and resident of New York, in the county of New York and State of New York, have invented certain new and useful Improvements in Expression Devices for Mechanical Musical Instruments, of which the following is a full, clear, and exact specification.

10 This invention relates to mechanically operated musical instruments of the class in which the motive force for causing the notes to sound is pneumatic pressure developed by bellows or similar means operated or controlled by the performer.

The invention consists in improved means for varying at will either suddenly or slowly, the intensity of the pneumatic pressure, so that the notes may be sounded loudly or 20 softly, and thereby overcome the monotony so common in music produced by mechanical means.

Although the invention is applicable to either pressure or exhaust apparatus, it is 25 here shown in connection with a mechanical piano player in which the piano keys are struck by mechanical fingers, operated by a series of pneumatic motors, the operation of which is induced by exhaust apparatus:

30 In the customary construction of instruments of this kind, the air is exhausted from a collapsible storage or reservoir bellows or compartment by means of smaller bellows known as "pumpers" or "supply" bellows, 35 operated by the feet of the performer. The reservoir bellows is connected by suitable passages with the motors or other actuating devices of the instrument, and is provided with springs, which tend to expand it against 40 the pressure of the outer atmosphere. When the amount of air drawn from the actuating devices into the reservoir bellows is in excess of the amount withdrawn by the pumpers, the bellows expands by the action of the 45 springs, and thus gives increased space for the excess of air supply. On the other hand, when the amount of air admitted is less than the amount drawn out by the pumpers or supply bellows, the springs yield and permit 50 the reservoir bellows to contract, thus preventing the creation of an excessive vacuum. An approximately uniform tension or degree of vacuum is thus continually maintained within the reservoir bellows in spite of the 55 ordinary irregularities in the pumping, or of ordinary variations in the amount of air ad-

mitted through the actuating devices. Some degree of variation may be obtained, due to the circumstance that the springs of the reservoir bellows gradually become stiffer as they 60 are compressed, thus providing a vacuum tension which is somewhat higher when the bellows is collapsed than when the bellows is expanded, thereby producing slight and gradual variations in the loudness of the 65 notes. But this ordinary construction does not permit of obtaining such instantaneous and pronounced changes in the vacuum as are required for sharply accenting one note as compared with the note which immediately 70 precedes it, the intended and characteristic function of the equalizing reservoir being to prevent these very changes.

In the present invention means are provided for instantaneously cutting the equalizing reservoir out of operation at the will of the operator. In the embodiment shown and described herein, a substantially non-collapsible and non-equalizing chamber is employed in conjunction with the pneumatic 80 system, and preferably remains at all times connected with the pumping bellows or exhausting means, thus providing a moderate extent of permanent storage area. This special chamber may, however, be omitted 85 if a sufficient non-collapsible area is otherwise provided in connection with the pneumatic system. The collapsible equalizing reservoir, which may be of the customary bellows construction, operates in the ordinary way when connected with the system, to equalize the tension. But when the equalizer is cut out of operation the pumpers are enabled to increase the tension in the chamber to any desired degree, up to the 90 capacity of the pumpers. Provision is also preferably made whereby the equalizing function of the bellows will be automatically restored to the pneumatic system, whenever the vacuum therein falls below the minimum 100 predetermined by the tension of the equalizer springs.

Figure 1 is a sectional side view of part of a mechanical piano player showing one embodiment of the invention, the section being 105 taken on the lines 1—1 of Figs. 2 and 3. Fig. 2 is a sectional rear view of part of Fig. 1, the section being taken on the line 2—2 of Fig. 1. Fig. 3 is a plan view of Figs. 1 and 2, looking at right angles to the line 3—3 of 110 Fig. 1. Fig. 4 is a partial sectional side view and shows a modified form of the invention.

Fig. 5 is a side view of another modified form. Fig. 6 is a sectional rear view of part of Fig. 5, the section being taken on the line 6—6 of Fig. 5, looking in the direction of the arrow. Figs. 7 and 8 are side views in section of further modifications of the invention.

The two pumbers or supply bellows 15 which exhaust the air from the apparatus are constructed in any usual manner and are operated by pedals 13, worked by the feet of the performer and connected to the pumbers 15 by the straps 14. The partition 17 forms the stationary leaf of the pumbers and forms also one side of the intermediate air chamber 18. The opposite side of the wind chamber consists of a panel 21 which forms the stationary leaf of the reservoir or equalizer bellows 19. This bellows is of the usual type and is provided with springs 20 tending to press it open. The intermediate chamber is substantially non-collapsible, although it is preferably made so that one or more of the sides will spring inwardly under high tension to a sufficient extent to soften the more abrupt changes, and obviate harshness of contrast. The panel 21 is separated from the partition 17 along its upper portion by the top 23 and at its lower portion by blocks 56, of which there are preferably two, located at opposite ends of the panel. The bottom 54 and the ends 55 of the chamber 18 are formed of leather or some suitably flexible material, which for convenience in manufacture may be a continuation of the bottom and sides of the store bellows 19. The partition 17 is provided with the usual valve leather 16, thus enabling the pumbers to exhaust the chamber 18 in a manner similar to the customary method of exhausting the reservoir bellows. A passage 24 connects the chamber 18 with the wind chest of the actuating devices, which may be of any well-known construction, and are so well understood that a description of them is here unnecessary. An opening 25 is formed in the panel 21 and is provided with a valve 26 which is normally held open against the action of the spring 27 by the wedge 31, arranged to slide on the panel 21 between the gibs 32. The valve 26 is provided with an arm 28 which rests upon the straight portion 34 of the wedge when the latter is in its lowest position, thus keeping the valve open and permitting the air to pass freely through the opening 25 from the chamber to the bellows and vice versa.

The wedge 31 is moved by means of the lever 36 which fits in the slot 37 at one end of the wedge and has a long fulcrum 38 which extends through and is supported by the panel 21 and the partition 17. The outer end of the fulcrum 38 carries an arm 39 which is connected by the rod 42 (Fig. 2) with the vertical arm 44 of the rock shaft 43 supported on the casing 11 of the instrument.

The rock shaft carries a horizontal arm 45 which is connected at its outer end to the button rod 49 on top of which is the button 48 (Fig. 1). A spring 50 engages the button on its under side and keeps it normally above the level of the top 12 of the instrument, thus holding all the parts in their inoperative position, the wedge 31 being at its lowest position so as to hold the valve 26 open. With the parts in this position the store bellows 19 operates as usual, and approximately equalizes the vacuum by means of the spring 20, expanding and contracting according to the variations in the pedaling and the fluctuations in the amount of air drawn in through the actuating devices. The action in this case is the same as if the bellows 19 were connected directly with the pumbers 15, as in the usual construction, without the intervention of the chamber 18. Thus by pedaling rapidly, a slightly increasing tension may be obtained. On the other hand, by pumping slowly or ceasing entirely, a slightly decreasing tension is obtained as the bellows expands.

If the button 48 be depressed to the position shown in Fig. 1, the motion imparted to the rock shaft 43 will swing the arm 39 and the lever 36 so as to raise the wedge 31 and release the lifter 28, thus allowing the spring 27 to close the valve 26 and cut off the communication between the bellows 19 and the chamber 18. A very high tension may now be instantly obtained in the chamber 18, since the small capacity and non-collapsing character of the chamber enables it to be quickly exhausted by a stroke or perhaps even less, of one of the pumbers, the greater air pressure in the bellows 19 keeping the valve 26 tightly closed. If now the button 48 be released, a low vacuum will be instantly provided independent of the action of the pumbers, since the button spring 50 will at once open the valve 26 by moving the wedge 31 downward so that the beveled surface 33 carries the valve arm 28 outward to the flat surface 34, thus putting the bellows 19 again into communication with the chamber 18, and causing an instant lowering of the pressure by equalizing it on the two sides of the panel 21. Slower pedaling will also create a low vacuum even though the button is not released. If the vacuum in the chamber falls appreciably below the tension to which the store bellows 19 is adjusted, the valve 26 opens, and thus puts the store bellows 19 in action automatically. Thus the performer may instantly create all desired degrees of vacuum from the lowest to the highest by depressing the button and properly operating the pedals, without necessarily releasing the button to return to any desired lower tension.

In order to preclude the possibility of the bellows 19 ever being fully expanded and

therefore inoperative when called into use, the small packages 57 in the posts 56 are provided, through which the pumpers 15 will always act to some extent on the bellows 19, 5 since their connection is entirely independent of the chamber 18 and the valve 26. Thus the bellows 19 is always being slowly exhausted even during the time the button 48 is depressed, thus being always in readiness 10 to assume its customary function automatically when the tension falls to the degree for which it is adjusted. The panel 21, while stiff enough to prevent any considerable reduction of the capacity of the chamber 18, 15 is flexible enough to yield more or less to the unequal pressure on its opposite sides, returning at once to its original position as soon as the inequality disappears. This elasticity is an important feature since it 20 compensates for irregularities in the pumping, and thereby materially contributes to the smoothness of the action.

In the modified construction shown in Fig. 4 the valve 66 and its spring 67 are similar to those of the former figures. The valve is operated by a bar 69 which slides endwise through the partition 17 and engages the valve on its under side through the opening 25. It is connected to the button 48 by 30 means of the rod 79 and the arms 73 and 75 secured to the pivot 74 mounted in the bracket 76 secured to the casing 11. It may operate directly on the valve 66, or if desired, a small relief flap 68 may, as shown in 35 this figure, be provided for the valve 66 to ease the opening action by reducing the area of resistance in case of an extreme difference in pressure on the two sides of the valve. The initial movement of the rod 69 opens the 40 small flap 68 and at once relieves the pressure, the continued movement of the rod carrying the valve to its normally opened position. A pin 70 in the bar 69 extends across the small flap opening and engages 45 the under side of the main valve 66 as soon as the flap 68 has opened sufficiently.

In the modified construction shown in Figs. 5 and 6 the hinged valve is replaced by a slider 86, which is carried in a block 87 secured to the panel 21. Openings 89 are formed in the panel 21, and extend through the block 87. Similar openings 88 are 50 formed in the slider and are so disposed as to coincide with the openings 89 when the slider is in its wide open position, thus permitting free communication between the chamber 18 and the bellows 19. To one end of the slider 86 is attached the rod 90 which passes through the top 91 of the bellows and 55 is connected to the bell-crank 93, pivoted to the bracket 94. The slider is moved by the button 48 through the connecting rod 95, the arms 96 and 98 secured to the pivot 97, and the rod 100, the pivot 97 being supported 60 by the bracket 99 secured to the side 11 of

the casing. In this case, however, hinged valves 83 with springs 84 are provided to automatically restore communication between the chamber 18 and the bellows 19 when the vacuum in the chamber falls below that in the bellows. 70

In Figs. 7 and 8 modified forms of the invention are shown, operated by pneumatic means. In Fig. 7, the wedge 34 which opens the valve 26 has attached to it a rod 101 75 which passes through the top of the bellows 19 and is connected to the movable leaf of a motor pneumatic 102 secured in a suitable position near the top of the instrument. A primary box 103 has pallets 107 and 108 secured to the stem 104 of the button 48. When the button is depressed the motor 102 is exhausted through the tube 105 by means of the tube 106 which may connect with the bellows 19 or with the exhaust supply in any 80 suitable or convenient manner. The diaphragm 109 having atmospheric pressure on one side of it, and a partial vacuum on the other side, operates in place of a spring to return the button 48 to its normal position, 85 as soon as the button is released. Springs placed in the interior of the motor 102, or in any other suitable position, return the wedge 34 to its normal position as soon as the motor 102 is cut off from the exhaust. 90

In Fig. 8 the motor pneumatic 114 is secured inside the bellows 19 upon the panel 21, and has a link 116 connecting it with the valve 115. The interior of the motor 114 is connected by means of the passage 117 and 100 the tube 118 with a primary box similar to that of Fig. 7, the exhaust pipe 119 of the primary 113 being shown in this case as directly connected with the bellows 19. When the button 48 is in its normal position the 105 bellows 114 is expanded since it has atmospheric pressure inside and is surrounded by the partial vacuum in the bellows 19, thus holding the valve 115 open against the pressure of the spring 120. When the button 48 is depressed the interior of the motor 114 is 110 exhausted, thus equalizing the pressure on both sides of it, and thus permitting the spring 120 to close the valve 115. In its deflated condition the motor 114 affords no 115 resistance to the opening and closing of the valve 115.

The embodiments of this invention herein shown and described are those which are believed to be best suited to the manner in 120 which the pneumatic devices of piano players are now most commonly constructed and arranged. In such instruments, compactness and directness of action are important considerations; hence in these embodiments, the pumping bellows and the non-collapsible chamber, and the equalizing reservoir are shown as being placed side by side and connected by passages leading directly from one to the other. The flexible 125 130

panel or side wall 21 as herein shown is utilized as the partition between the non-equalizing chamber and the reservoir; and is also utilized to carry the valve mechanism by which the latter is connected and disconnected from the pneumatic system. But these are not essential features of the invention, and may be modified in various ways. The passage 25 which connects the reservoir and the chamber directly through the partition 21 may be carried through any other of the walls of those chambers, by tubing or otherwise, and the valve 26 which controls that passage may be placed at any convenient point in the connecting tubing; and may thus be removed entirely from the interior of the storage reservoir. In many other ways which will suggest themselves to those familiar with this art, the embodiment herein shown may be modified in construction, arrangement and relative position, to suit different environments or to suit various conditions of service.

I claim as my invention:—

- 25 1. In a pneumatic player for musical instruments, the combination of an air pump, a resiliently contractible but non-collapsible chamber, an equalizing reservoir communicating with the chamber, a check valve arranged to open and close the said communication automatically under the control of the preponderating air pressure in the chamber and the reservoir, respectively, and means for interrupting and restoring the free operation of the check valve.
- 30 2. In a pneumatic player for musical instruments, the combination of an air pump, a resiliently contractible but non-collapsible air chamber, an equalizing reservoir communicating with the said chamber, and means for opening and closing the said communication.
- 35 3. In a pneumatic player for musical instruments, the combination of an air pump, a non-collapsible chamber provided with a wall having a substantial degree of resiliency, an equalizing reservoir communicating with the said chamber, a valve arranged to close the said communication from the reservoir side thereof whereby it is automatically opened by excess of pressure in the chamber, and manually operated means for interrupting and restoring the free operation of the check valve.
- 40 4. In a pneumatic player for musical instruments, the combination with the exhaust passages thereof, of an air pump, a non-collapsible chamber provided with a wall having a substantial degree of resiliency, an equalizing reservoir, and means for opening and closing communication between the equalizing reservoir and the said passages.
- 45 5. In a pneumatic player for musical instruments, the combination of an air pump and exhaust passages, an equalizing reser-

voir separated from the said passages by a wall having a substantial degree of resiliency, an air opening between the said passages and the said reservoir, a check valve normally operating to close the said opening, means for holding the said valve open during the ordinary playing of unaccented notes, and manually controlled means for releasing the valve to permit its free normal action.

6. In a pneumatic player for musical instruments, the combination of an air pump, a substantially non-collapsible air chamber communicating therewith, an equalizing reservoir separated from the said chamber by a resiliently flexible wall, provided with an opening communicating between the reservoir and the chamber, a check valve yieldingly closing the said opening, means for holding the said valve open during the ordinary playing of unaccented notes, and manually controlled means for releasing the valve at the will of the operator, to permit its free normal action.

7. In a pneumatic player for musical instruments, the combination of an air pump, a non-collapsible chamber communicating therewith, an equalizing reservoir, means for opening and closing communication between the chamber and reservoir and a relatively small passage communicating between the reservoir and the air pump, independently of the chamber.

8. In a pneumatic player for musical instruments, the combination of an air pump, a non-collapsible air chamber communicating therewith, an equalizing reservoir, means for opening and closing communication between the chamber and the reservoir, and a relatively small air passage communicating between the reservoir and the air pump independently of the chamber.

9. In a pneumatic player for musical instruments, the combination of an air pump, a non-collapsible air chamber communicating with the pump and provided with a wall having a substantial degree of resiliency, an equalizing reservoir, means for opening and closing communication between the reservoir and the chamber including a check valve arranged to be closed by preponderance of air pressure in the reservoir over the pressure in the chamber, and means under the control of the operator for interrupting and restoring the free operation of the valve.

10. In a pneumatic player for musical instruments, the combination of an air pump, a resiliently contractible but non-collapsible chamber communicating with the pump, an equalizing reservoir communicating with the chamber by an air passage, a spring-pressed valve normally operating to close the said passage from the reservoir side, and externally controlled means for interrupting and restoring the free operation of the valve.

11. The combination with a pneumatic in-

strument, of a substantially non-collapsible air chamber provided with a resilient wall unyieldingly supported at some portions, and flexibly connected to the other walls at 5 other portions.

12. The combination with a pneumatic instrument, of an air chamber having a resilient wall, some portions of which are provided with a flexible connection with the 10 other walls of the chamber and other portions of which are provided with a plurality of substantially unyielding supports to render the said air chamber substantially non-collapsible.

15 13. In a pneumatic player for musical instruments, the combination of pumping means, a substantially non-collapsible air chamber connected therewith having a resilient wall inflexibly secured at one edge and joined along its other edges to the other walls of the chamber by a flexible casing, and means for unyieldingly supporting the resilient wall at a plurality of separated points remote from the inflexible edge.

25 14. In a pneumatic player for musical instruments, the combination with the pneumatic system thereof, of pumping means, a substantially non-collapsible air-chamber connected therewith having a resilient wall inflexibly secured at one edge and joined along its other edges to the other walls of the chamber by a flexible casing, means for unyieldingly supporting the resilient wall at a 30

plurality of separated points remote from the inflexible edge, equalizing devices, air passages connecting the pumping means, the chamber, and the equalizing devices to the pneumatic system, and means for closing the communication between the pneumatic system and the equalizing devices. 35

15. In a pneumatic player for musical instruments, the combination with the pneumatic system thereof, of pumping means, equalizing devices, a substantially non-collapsible air-chamber disposed between the 40 pumping means and the equalizing devices, said chamber having a resilient wall inflexibly secured along one edge and joined along its other edges to the other walls of the chamber by a flexible casing means for unyieldingly supporting the resilient wall at a plurality of separated points remote from the inflexible edge, air passages connecting the chamber with the pneumatic system, the pumping means, and the equalizing devices, 45 and means for closing the communication between the chamber and the equalizing devices. 50

In testimony whereof I have signed my name to this specification in the presence of 60 two subscribing witnesses.
